(57) **CLAIM**

The ornamental design for a pet collar imprinting kiosk, as shown and described.

DESCRIPTION

FIG. 1 is a top, front, left side perspective view of a pet collar imprinting kiosk showing our new design;

FIG. 2 is a top, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

The bottom view of the pet collar imprinting kiosk is not part of the claimed design.
